DESIGN FOR A TEXTILE PILE FABRIC

Juanita Todd, Yonkers, N. Y., assignor to Sidney Blumenthal & Co., Inc., New York, N. Y., a corporation of New York

Application July 2, 1935, Serial No. 57,485

Term of patent 7 years

To all whom it may concern:

Be it known that I, Juanita Todd, a citizen of the United States and resident of Yonkers, in the county of Westchester and State of New York, have invented a new, original, and ornamental Design for a Textile Pile Fabric, of which the following is a specification, reference being had to the accompanying drawing, forming a part thereof:

The figure is a plan view of a textile pile fabric showing my new design; the design residing in an arrangement of contrasting pile tufts substantially as shown, the drawing being marked to indicate one repeat unit of the design.

I claim:

The ornamental design for a textile pile fabric substantially as shown and described.

JUANITA TODD.
